Specification of Letters Patent. Patented Sept. 11, 1917.

Application filed January 29, 1914. Serial No. 815,127.

To all whom it may concern:

Be it known that I, THOMAS H. SEELY, a citizen of the United States, residing at Dorchester, Boston, in the county of Suffolk 5 and State of Massachusetts, have invented certain new and useful Improvements in Sewing-Machines; and I do hereby declare the following to be a full, clear, and exact description of the invention, such as will enable others skilled in the art to which it appertains to make and use the same.

This invention relates to sewing machines, and more particularly to curved hook needle sewing machines employed in sewing together the soles and uppers of shoes, and known in the art as inseam shoe sewing machines.

Curved hook needle sewing machines used in the manufacture of shoes to sew together 20 the soles and uppers are usually provided with a back gage which supports the shoe against the backward pull of the needle as the needle retracts from the work. In the present commercial machines of this class 25 the back gage is moved backward away from the shoe before the shoe is fed so that the upper will not be wrinkled by the frictional contact of the back gage therewith during the feed movement of the shoe. 30 After the shoe is fed, the back gage is moved forward into contact with the shoe and is locked in operating position before the needle retracts so that it may furnish a rigid abutment to resist the needle pull. 35 The back gage mechanism of machines of this class heretofore produced, have been so constructed that the thrust of the moving parts of the back gage mechanism is received by the shoe as the back gage strikes 40 the shoe during its forward movement. The result has been that the back gage pounds against the shoe during the sewing operation and makes it difficult for the operator to hold the shoe in position.

45 The objects of the present invention are to improve the construction and mode of operation of certain parts of inseam shoe sewing machines and to provide inseam shoe sewing machines with an improved back 50 gage mechanism constructed and arranged to eliminate the pounding of the back gage against the shoe.

With the above objects in view, the invention comprises various novel and improved features of construction, arrange-

ments and combinations of parts set forth in the following description and pointed out in the claims, the advantages of which will be obvious to one skilled in the art.

In the drawings illustrating a machine 60 embodying the various features of the invention in their preferred forms, Figure 1 is a view in side elevation of the machine; Fig. 2 is a view in side elevation, illustrating a portion of the machine looking 65 from the same side thereof as in Fig. 1; Fig. 3 is a view in vertical section of the mechanism shown in Fig. 2; Fig. 4 is a view in side elevation of a portion of the machine looking from the same side of the 70 machine as in Fig. 1; Fig. 5 is a view partly in side elevation and partly in section illustrating particularly the mechanism for locking the back rest slide; Fig. 6 is a sectional view taken substantially on the line 6—6 75 of Fig. 5; Fig. 7 is a detail view partly in section illustrating certain parts of the mechanism shown in Figs. 5 and 6; Fig. 8 is a detail view in horizontal section illustrating a portion of the mechanism for re- 80 tracting the welt guide slide; Fig. 9 is a detail view partly in side elevation and partly in section of the mechanism illustrated in Fig. 8; Fig. 10 is a sectional view taken substantially on the line 10—10 of 85 Fig. 9; Fig. 11 is a detail view illustrating certain parts of the mechanism shown in Figs. 8 and 9; Fig. 12 is a sectional view taken substantially on the line 12—12 of 90 Fig. 1; Fig. 13 is a detail view in side elevation illustrating particularly the looper and the thread clamping and thread cutting devices attached to the looper arm; Fig. 14 is a view illustrating the looper and 95 attached parts looking in the direction of the arrow b, Fig. 13; Fig. 15 is a view of the parts shown in Fig. 13, looking in the direction of the arrow a in said figure; Fig. 16 is a detail view illustrating parts of the welt guide mechanism; and Fig. 17 is a de- 100 tail sectional view taken substantially on the line 17—17 of Fig. 16.

The machine embodying the various features of the invention as illustrated in the drawings is a shoe sewing machine of the 105 class employing a curved hook needle and devices coöperating therewith to form a chain stitch, and is particularly designed for sewing the inseams of welted shoes, although with slight changes hereinafter pointed 110

out it may be used in sewing together the uppers and soles of turned shoes. The curved hook needle indicated at 2, the needle guide 4, the thread finger 6, and the channel guide 8, are all constructed and arranged in the same manner, and are operated by the same mechanism as the corresponding parts of the machine illustrated in the patent to Andrew Eppler, No. 1,108,560, dated August 10 25, 1914.

The looper of the machine illustrated in the drawings is actuated in substantially the same manner as the looper of the machine illustrated in the above Eppler patent. In 15 order to enable the looper to be heated more efficiently than has been done heretofore, certain changes have been made in the mechanism for supporting and actuating the looper, as will now be described. The looper indicated at 10 is secured by a screw 12 to the lower end of an arm 14 pivoted intermediate its ends to oscillate in a plane perpendicular to the plane of the needle upon the forward end of a slide 16, which slide is arranged to reciprocate in a direction substantially parallel with the plane of the needle. The upper end of the arm 14 is provided with a socket or bore to receive a stud projecting from a sleeve 18, which forms a bearing to receive a rod 20 secured to the outer end of an arm 22 carried by a rock shaft 24. A second arm 26 is secured to the rock shaft 24, and carries a cam roll which engages a cam groove in a cam disk mounted 30 on the main shaft of the machine. Forward and rearward movements are imparted to the looper by the reciprocation of the slide 16, and the oscillation of the arm 14 swings the looper in a plane substantially perpendicular to the plane of the needle, the movements of the slide and the arm being relatively timed to carry the looper about the needle. A block 28 is secured to the forward end of the slide 16, and embraces the arm 40 14, as illustrated in Fig. 12. The arm 14 is supported on the slide by means of a hollow shaft 30 passing through suitable bearings in the arms of the block 28 and in the central portion of the arm 14. The chamber in 45 the shaft 30 does not extend completely through the rear end of said shaft, and the forward end of the chamber is closed by a plug 32 screwed into the end of the shaft. This chamber is connected by a coupling 50 34 with a pipe 36 which leads from a steam chamber in a plate 38 forming a part of the frame of the head of the machine. The steam is conducted from the generator to the chamber in the plate 38 by means of inlet pipes 40 and 42. The steam is led from the chamber in the shaft 30 by means of an outlet pipe 44 connected at its forward end with said chamber. To hold the hollow shaft 30 securely from longitudinal movement, a bracket 44^a is secured to the plate

38, and is provided with a downwardly extending arm which engages a groove in the connection 34. By providing a steam chamber in the shaft 30 upon which the looper carrying arm is pivoted, this arm and the looper itself are heated in an efficient manner so that the wax thread as it passes from the looper eye is in a proper condition for sewing a satisfactory tight seam.

The mechanism for heating the looper as 75 above described is covered in an application Serial No. 133,620, filed November 27th, 1916, which constitutes a division of the present application.

The machine is provided with the usual 80 welt guide indicated at 48, which is provided with a welt guiding passage and acts to conduct the welt to the sewing point and position it properly with relation to the shoe. As is usual in this type of machine, after 85 the work has been fed the welt guide is moved forward into engagement with the shoe before the needle advances to pierce the work, and is held in engagement with the work until after the needle retracts from the 90 work, so that it forms an abutment for the work to resist the backward pull of the needle thread as the needle retracts. Before the shoe is fed the welt guide is moved back out of contact with the work, so that the 95 upper will not be rumpled by contact with the welt guide therewith during the feed movement of the shoe. The welt guide is mounted upon the lower end of a carrier 50 pivoted at 52 above and in front of the axis 100 of the needle. The welt guide is adjustably secured to the lower end of the carrier by means of a screw 54 engaging a slot in the carrier, and is held from turning on the screw by means of a pin 56 engaging a 105 groove in the shank of the welt guide, as shown in Fig. 2. The welt guide is moved toward and from the shoe by the movements of an actuator 58 which in the construction illustrated consists of a slide mounted for 110 forward and rearward movements in guides in the frame of the machine, and connected at its forward extremity to the carrier 50. The mechanism for moving the actuator slide 58, which will be hereinafter described, 115 is constructed and arranged to move the slide in a path having definite limits.

The forward end of the actuator slide is connected with the carrier by a link 60 and a locking device which acts to lock and unlock the forward end of the link with relation to the carrier during each cycle of operations. The link 60 carries at its forward end a pin 62 to which is pivoted a locking block 64 engaging in a slot 66 in the carrier 50. The width of the locking block is somewhat less than the width of the slot 66, and the block is provided with faces 68 arranged at an angle to the side faces of the block, so that when the block is turned into 125 130

the position shown in Fig. 16, the faces 68 of the block will frictionally engage the side faces of the slot and lock the carrier to the forward end of the link 60. By turning the block to the right, Fig. 16, the locking faces of the block will be disengaged from the side faces of the slot to unlock the carrier with relation to the link. In the present embodiment of the invention, as the 5 slide 58 is moved forward to bring the welt guide into contact with the shoe, the carrier is locked to the forward end of the link 60 until the slide has executed a portion of its forward movement, sufficient to move the 10 welt guide nearly into engagement with the shoe, and is then unlocked so that the welt guide can move forwardly independently of the link and slide and that when the welt guide engages the shoe it can yield with relation to these parts. A comparatively light 15 spring 70 is provided having one extremity engaged in the frame and the other in the carrier 50, and acts to give the final forward movement to the carrier to bring the welt 20 guide into engagement with the shoe after the carrier is unlocked with relation to the link 60. With this construction, as the welt guide strikes the shoe the shoe receives the thrust only of the welt guide and carrier 25 and that of the spring 70, all of which parts are relatively light so that there is no appreciable pounding of the welt guide against the shoe. Before the needle is retracted from the work, the welt guide carrier is 30 locked to the forward end of the link 60 so that the work is supported against the backward pull of the needle. The carrier remains locked to the link during the retracting movement of the actuator slide to carry 35 the welt guide away from the shoe so that the welt guide is always retracted substantially the same distance from the work, regardless of the thickness of the work, and is not unlocked until the slide has executed 40 part of its forward movement to move the welt guide into contact with the shoe, as above described.

The mechanism for turning the locking block to lock and unlock the carrier with relation to the link 60 and the welt guide actuator slide in timed relation to the other parts of the machine, comprises an arm 72 upon which the locking block 64 is formed, said arm having at its rear end a pin or stud 74 50 connected by a spring 76 with a pin 78 carried by a bracket 80. This spring acts to turn the locking block in a direction to lock the carrier to the link 60 and slide 58. To permit the tension of the spring to be adjusted, the bracket 80 is mounted for vertical adjustment on a pin 82 and is held in adjusted position on the pin by a set screw 84. The arm 72 is swung upwardly or in a direction to unlock the carrier 50 with relation to the link 60 and the slide 58 by

mechanism comprising a link 86 having a slot 88 at its upper end in which the pin 74 is received and pivoted at its lower end to an arm 90 secured to a rock shaft 92 mounted to turn in a bearing 94 in the frame. The 70 other end of the rock shaft carries an arm 96 connected by a link 98 with the forwardly extending horizontal arm of a lever 100—102 pivoted on a stud 104 and carrying a cam roll 106 which engages the peripheral cam surface of a cam disk mounted on the main shaft of the machine. The depression of the arm 100 acts through the connections described, to lift the link 86 and thereby actuate the arm 72 to unlock 80 the carrier with relation to the link 60 and the slide 58.

The actuator slide 58 is moved forwardly to move the welt guide into contact with the shoe by means of a spring 108 coiled about 85 a stud 110 and secured at one end to a cap 112 mounted on the stud, said spring having an upwardly extending arm which engages a pin 114 on the slide. The slide 58 is retracted to carry the welt guide away from 90 the shoe by the rearward movement of a reciprocating block 116 embracing the slide 58 and having an arm 118 pivoted at 120 thereon. This arm is provided with shoulders 122 and 124 having a stepped arrangement, as shown in Fig. 8, of which the shoulder 122 normally engages an abutment 126 on the slide. The arm 118 is held in the position shown in Fig. 8, with the shoulder 122 engaging the abutment 126 by a spring 100 128 connected at one end with a pin secured in the arm 118, and at the other end with a pin secured in the block 116. The slide 58 is retracted by the engagement of the shoulder 122 with the abutment 126 as 105 the block 116 is moved rearwardly, and the slide is advanced as the block 116 is moved forwardly by the action of the spring 108. The mechanism for actuating the block 116 110 comprises a link 130 pivotally connected at its forward end with the block 116, and at its rear end with the lower arm of a lever 132 pivoted on a stud 134, and provided at the end of its upper arm with a cam roll 115 which engages a cam groove in a cam disk carried by the main shaft. To permit an adjustment of the limits of the movement of the block 116, and of the slide 58, the lower arm of the lever 132 is provided with a slot 136, and the link 130 is connected with the 120 lever by a pin or bolt 138 adjustably secured in this slot. In the illustrated embodiment of the invention, the slide 58 is not positively locked in position during the retracting movement of the needle, but the spring 125 108, together with the springs 70 and 76 and the frictional resistance to the rearward movement of the slide 58, hold the welt guide from retraction during the backward pull of the needle.

When the seam has been completed it is desirable that the welt guide should be drawn back to the rear of its normal retracted position so that it will offer little or no obstruction to the removal of the shoe and the insertion of another shoe in operating position. In machines of the class illustrated, after the shaft has been stopped at the end of the sewing operation, it is usual

10 to reverse the direction of rotation of the shaft so as to unhook the last loop of thread which has been drawn through the work by the needle from the needle, and to finally bring the shaft to rest with the needle in

15 retracted position out of engagement with the work. In the present embodiment of the invention, mechanism actuated during the reverse rotation of the shaft is provided for retracting the slide 58 while the lower

20 arm of the lever 132 is in advanced position, so that the shoulder 124 of the arm 118 will engage in front of the abutment 126. Then when the lower arm of the lever 132 swings toward the rear of the machine, said

25 lever will act to retract the welt guide to the rear of its normal retracted position. In the construction illustrated, this mechanism comprises a lever 140 pivoted on a stud 142, and having a pin 144 mounted

30 upon its upper end, which pin engages in a slot 146 in the rear end of the slide 58. A coiled spring 148 is interposed between the lever 140 and an abutment on the frame of the machine, and acts to maintain the

35 lever normally in forward position. When the lever 140 is swung rearwardly, the pin 144 engages the rear end of the slot 146, and the slide 58 is thereby retracted. The mechanism for swinging the lever comprises

40 a lever 150 pivoted on a stud 152 and connected with the lever 140 by a link 154 having a slot 156 in its forward end in which engages a pin 158 mounted on the lever 140. The upper arm of the lever 150 is connected

45 by a link 160 with the arm 162 of a lever 162-164 pivoted on the stud 104. A swinging arm 166 is pivotally connected at its rear end with the upper end of the arm 164, and is provided with curved faces 168 and

50 170 for engagement with a collar 172 mounted on the main shaft of the machine. The curved face 170 on the arm is formed at a greater distance from the axis of movement of the arm than the curved face 168.

55 During the normal operation of the machine, the arm 166 is supported with the surface 168 of the arm engaging the collar 172, as shown in Fig. 1. Upon a reversal in the direction of rotation of the main

60 shaft of the machine, the arm 166 is swung upwardly and moved rearwardly to bring the curved face 170 into engagement with the collar 172 by the engagement of the end face of a recess 174 in the collar with a tooth

65 176 on the arm 166 located between the faces

168 and 170. As the recess 174 arrives at a point opposite the tooth 176, the arm 166 is lifted slightly to engage the tooth in the recess by means of a spring 178. When the arm 166 is actuated to engage the curved face 170 with the collar 172, the arm 164 of the lever 162-164 is swung to the rear, thereby, through the mechanism described, swinging the lever 140 rearwardly to retract the slide 58 with relation to the block 116, and allow the lever 118 to swing inwardly to bring the shoulder 124 in front of the abutment 126 on the slide. The slide is thus retracted while the lower arm of the lever 132 is in forward position, and when the lower arm of said lever swings to the rear, the slide 58 will be moved back a distance to the rear of its normal retracted position equal to the distance between the shoulders 122 and 124, so that it will present no obstruction to the removal of the shoe, or the insertion of another shoe in the machine. To release the shoulder 124 from the abutment 126, and allow the slide 58 to move forwardly to bring the shoulder 126 into engagement with the abutment upon starting the machine, the lever 118 is provided with a shoulder 180 which, when the block 116 moves forward, engages a projection 182 upon a plate 184 secured to the frame, and the lever 118 is thereby swung in a direction away from the slide, so as to permit the slide and the lever 118 to assume their normal relations.

186 indicates the usual back rest with which machines of this class are provided. The back rest is mounted on the forward end of a slide 188, and is moved forward by the action of a spring actuated arm 190 which engages a pin 192 mounted on the slide, as shown and described in the above Eppler patent. Mechanism is provided for locking the slide in timed relation to the other parts of the machine in substantially the same manner as is usual in this type of machine. In the present embodiment of the invention, however, improved mechanism is provided for locking the slide. The slide locking mechanism in the construction illustrated comprises a locking lever 194 pivoted on a stud 196 mounted on the frame, which stud engages a slot 198 in the lever. The lever is provided with clamping jaws 200 and 202 which embrace a flange or rib 204 on the slide 188. As shown particularly in Figs. 5 and 7, the jaw 200 is arranged somewhat in advance of the jaw 202, so that as the lower end of the lever is swung forwardly from the position in which it is shown in these figures, the flange on the slide will be permitted to move freely between the jaws and that when the lower end of the lever is swung rearwardly the jaws will bite against the rib 204 and lock the slide in position. The lower end of the

lever 194 is swung to the rear to lock the slide by means of a coiled spring 206 attached at one end to the frame, and at the other end to the lower arm of the lever. 5 With this construction, after the lever has been swung into position to lock the slide, any tendency to displace the slide rearwardly will cause the lever to lock the slide more securely. The lever is actuated during each cycle of operations to unlock the slide so that the back rest may be moved forwardly into contact with the shoe by mechanism which comprises a link 208 pivotally connected at 210 with the lever, and 10 carrying at its rear end a pin 212 which engages a slot 214 in the lower end of the arm 102 of the lever 100—102. This is the lever which acts to unlock the welt guide carrier with relation to the forward end of the link 208, and the welt guide carrier is unlocked with relation to the link and actuator slide, and the back rest is unlocked so that it can move forward into engagement with the work at the same time by the action of this 15 lever.

25 Although in the illustrated embodiment of the invention the machine is fitted for sewing together the uppers, welts and insoles of welt shoes, it may be fitted for sewing together the soles and uppers of turned shoes merely by detaching the welt guide from the carrier 50 and substituting a back gage of ordinary construction therefor. The welt guide in the machine illustrated performs 30 the same function as the back gage of the machine when fitted for sewing turned shoes, in that it supports the shoe against the backward pull of the needle as the needle retracts from the work. The term back gage is often 35 applied to the welt guide of an inseam sewing machine. Accordingly, in the claims the term back gage is employed and applies to the welt guide of a machine fitted for welt shoe work as well as to the back gage of a 40 machine fitted for sewing turn shoes.

45 The machine is provided with a thread cutter by which the thread may be severed upon the completion of the seam, and with a thread gripping device for holding the free end of the thread during the beginning of a new seam. The thread gripping device is secured to the arm of the looper and comprises clamping plates 216 and 218 secured together by screws 220, and provided respectively with diverging clamping jaws 222 and 224 between which the thread is inserted by the operator in removing a shoe from the machine. A thread cutting knife 226 is clamped to the outer face of the 50 clamping plate 218 and is provided with a cutting blade at its left hand edge, Fig. 15, across which the thread is drawn to sever the same. It is undesirable that the thread gripping device should be kept heated to a high temperature, since when this device is

hot it will not hold the waxed thread in a reliable manner. In the construction illustrated, the thread gripping device is secured to the outer end of an arm 228 extending out from the looper, as shown in Fig. 15, by 55 a screw 230 passing through a slot in a projection or lug on the plate 216 and screwed into the end of the arm 228. With this construction, the thread gripping device is spaced from the looper and is, therefore, 60 maintained at a low temperature relative to that of the looper. To enable the thread clamping jaws to be relatively adjusted to suit different sizes of thread, the clamping plate 218 is provided on the side thereof, 65 opposite or facing the plate 216, with angularly arranged faces 232 and 234, the plate 218 engaging the plate 216 at the meeting point of these faces so that it may be rocked about this point to regulate the opening between the thread clamping jaws. The clamping plate 218 is adjusted about its point of engagement with the plate 216 by 70 suitable adjustment of the screws 220.

75 The thread gripping and thread cutting devices described above are covered in an application Serial No. 69,968, filed January 3, 1916, and constituting a division of the present application.

80 It is to be understood that except as defined in the claims the various features of the invention are not limited to any particular machine or type of machine, or to any particular construction and arrangement of parts.

85 Having explained the nature and object of the invention, and having specifically described a machine embodying the same in their preferred forms, what is claimed is:—

90 1. A shoe sewing machine, having, in combination, stitch forming devices including a curved hook needle, a back gage, a back gage actuator, means for moving the actuator to move the back gage toward and from the shoe, connections between the back 95 gage and the actuator comprising locking mechanism acting to lock the back gage with relation to the actuator during the retracting movement of the needle, during the 100 retracting movement of the actuator, and during the first portion of the forward movement thereof, and to unlock the back gage so as to permit relative movement between the back gage and the actuator.

105 2. A shoe sewing machine, having, in combination, stitch forming devices including a curved hook needle, a back gage, a back gage actuator, means for moving the actuator to move the back gage toward and from the shoe, connections between the back 110 gage and the actuator comprising locking mechanism acting to lock the back gage with relation to the actuator during the first portion of the forward movement of the actuator, and to unlock the back gage so as 115

to permit relative movement between the back gage and the actuator.

3. A shoe sewing machine, having, in combination, stitch forming devices including a curved hook needle, a back gage, a back gage actuator, means for moving the actuator to move the back gage toward and from the shoe, connections between the back gage and the actuator comprising locking mechanism acting to lock the back gage with relation to the actuator during the retracting movement of the actuator so that the back gage is always withdrawn substantially the same distance from the shoe, and to unlock the back gage so as to permit relative movement between the back gage and the actuator.

4. A shoe sewing machine, having, in combination, stitch forming devices including a curved hook needle, a pivoted back gage carrier, a back gage fixed to the carrier, a back gage actuator, means for moving the actuator to move the back gage toward and from the shoe, and connections between the actuator and the carrier comprising locking mechanism acting to lock and unlock the carrier with relation to the actuator during each cycle of operations.

5. An inseam shoe sewing machine, having, in combination, stitch forming devices including a curved hook needle, a back gage carrier, a back gage fixed to the carrier, a back gage actuator, means for moving the actuator to move the back gage toward and from the shoe, mechanism for locking and unlocking the carrier with relation to the actuator, comprising a locking block engaging a slot in the carrier, and means for turning the locking block in the slot to engage its faces with and disengage them from the sides of the slot and thereby lock and unlock the carrier with relation to the actuator.

6. An inseam shoe sewing machine, having, in combination, stitch forming devices including a curved hook needle, a back gage, a back gage slide, a lever for retracting the slide, connections between the lever and the slide comprising a block mounted to reciprocate adjacent the slide and connected with the lever, an arm movably mounted on the block and having stepped shoulders for engagement with an abutment on the slide, the forward of which shoulders normally engages the abutment, means for moving the slide rearwardly with relation to the block prior to the retracting movement of the lever, and means for moving said arm to bring the rear shoulder thereon into position to engage the abutment on the slide whereby the movement of the lever to retract the slide moves the back gage to the rear of its normal retracted position to permit the shoe to be more readily removed at the completion of the sewing operation.

7. An inseam shoe sewing machine, having, in combination, stitch forming devices including a curved hook needle, a back gage, a back gage slide, a lever for retracting the slide, connections between the lever and the slide comprising a block mounted to reciprocate adjacent the slide and connected with the lever, an arm movably mounted on the block and having stepped shoulders for engagement with an abutment on the slide, the forward of which shoulders normally engages the abutment, means for moving the slide rearwardly with relation to the block prior to the retracting movement of the lever, means for moving said arm to bring the rear shoulder thereon into position to engage the abutment on the slide whereby the movement of the lever to retract the slide moves the back gage to the rear of its normal retracted position to permit the shoe to be more readily removed at the completion of the sewing operation, and means to restore the arm and the slide to their normal relations.

8. An inseam shoe sewing machine, having, in combination, stitch forming devices including a curved hook needle, a back gage, a back gage slide, a lever for retracting the slide, connections between the lever and the slide comprising a block mounted to reciprocate adjacent the slide and connected with the lever, an arm movably mounted on the block and having stepped shoulders for engagement with an abutment on the slide, the forward of which shoulders normally engages the abutment, means actuated by a reversal in the direction of rotation of the main shaft of the machine for moving the slide rearwardly with relation to the block prior to the retracting movement of the lever, and means to move the arm to bring the rear shoulder thereon into position to engage the abutment on the slide whereby the slide is retracted by the retracting movement of the lever to move the back gage to the rear of its normal retracted position to permit the shoe to be more readily removed upon the completion of the seam.

9. An inseam shoe sewing machine, having, in combination, stitch forming devices including a curved hook needle, a back gage, a back rest, back gage and back rest slides, a lever for locking one of the slides having spaced jaws embracing a portion of the slide, and means for swinging the lever to cause the jaws thereof to bite against the slide and lock it in operating position.

10. An inseam shoe sewing machine, having, in combination, stitch forming devices including a curved hook needle, a back gage, a back rest, back gage and back rest slides, a lever for locking one of the slides having spaced jaws embracing a portion of the slide, a fixed fulcrum for the lever engaging a slot in the lever so that the lever is permitted to

slide along its fulcrum, and means to swing the lever about its fulcrum to cause the jaws thereof to bite against the slide and lock it in operating position.

5 11. An inseam shoe sewing machine, having, in combination, stitch forming devices including a curved hook needle, a back gage, a back rest, back gage and back rest slides, a lever for locking one of the slides having 10 spaced jaws embracing a portion of the slide, a spring for swinging the lever in a direction to cause the jaws to bite against the slide and lock it, and means for swinging the lever in the other direction during each 15 cycle of operations to unlock the slide.

12. A shoe sewing machine, having, in combination, stitch forming devices including a curved hook needle, a back gage, a back gage actuator, means for moving the actuator to move the back gage toward and from the shoe, connections between the back gage and the actuator comprising locking mechanism acting to lock the back gage with 20 relation to the actuator during the retracting movement of the needle, during the retracting movement of the actuator, and during the first portion of the forward movement thereof and to unlock the back gage so as to permit relative movement between 25 the back gage and the actuator, and means for moving the back gage forwardly with a light pressure independently of the actuator into engagement with the shoe.

13. A shoe sewing machine, having, in combination, stitch forming devices including a curved hook needle, a back gage, a

back gage actuator, means for moving the actuator to move the back gage toward and from the shoe, a connection between the back gage and the actuator permitting the back 40 gage to yield with relation to the actuator after the back gage engages the shoe, and means for locking the back gage to move with the actuator during the movement of the actuator.

45 14. A shoe sewing machine, having, in combination, stitch forming devices including a curved hook needle, a back gage, a back gage slide, means for moving the slide to move the back gage toward and from the shoe, a connection between the back gage and the slide permitting the back gage to yield with relation to the slide after the back 50 gage engages the shoe, and means for locking the back gage to move with the slide 55 during the movement of the slide.

15. A shoe sewing machine, having, in combination, stitch forming devices including a curved hook needle, a back gage carrier, a back gage fixed to the carrier, a back gage actuator, means for moving the actuator to move the back gage toward and from the shoe, a connection between the actuator and the carrier permitting the back gage to yield with relation to the actuator after the 60 back gage engages the shoe, and means for locking the carrier to move with the actuator during each cycle of operations.
